UNITED STATES PATENT OFFICE.

CHARLES A. BALLREICH, OF DES MOINES, IOWA.

CAR-COUPING.

SPECIFICATION forming part of Letters Patent No. 465,980, dated December 29, 1891.

Application filed March 5, 1891. Serial No. 383,895. (No model.)

To all whom it may concern:

Be it known that I, CHARLES A. BALLREICH, a citizen of the United States of America, and a resident of Des Moines, in the county of Polk and State of Iowa, have invented certain new and useful Improvements in Automatic Car-Couplers, of which the following is a specification.

My improvement relates to that class of car-couplers in which laterally-moving jaws pivoted to the draw-heads come into reciprocal engagement when two cars come together; and my invention consists in the construction and combination of a draw-head, pivoted jaw, and an automatic jaw-locking device, as hereinafter set forth, pointed out in the claims, and illustrated in the accompanying drawings, in which—

Figure 1 is a perspective view of a knuckle detached from the draw-head. Fig. 2 is a rear side view of the same. Fig. 3 is a vertical section through a portion of the draw-head and the knuckle when in an open and normal position. Fig. 4 is a side view of the swinging latch. Fig. 5 is a longitudinal sectional view of the draw-head, knuckle, and latch complete. Fig. 6 is a perspective view of my complete device in position as required for practical use.

30 A represents a draw-head having a concaved face.

B and B² represent ears formed integral with one side of the face of the draw-head and projecting forward therefrom. The ear B² has a cavity formed in its upper face, the bottom of which is inclined, and is adapted to admit a journal C to rotate therein. The journal C is tubular and formed integral with the lower face of the knuckle D, which 35 knuckle has a perforation therein coinciding with perforations in the ears B B² to admit a pivotal pin D². That portion of the knuckle D between the ears B B² is of less thickness than the distance between said ears, in order 40 that said knuckle may have vertical movement. A curved arm F is formed integral with and projects rearward from the knuckle D and works in and out of a horizontal angular slot formed between the ears B B² and 45 extending inward therefrom and across the face of the draw-head. The free end portion of the arm F is so constructed as to form 50

shoulders H, which engage against shoulders H², formed on the draw-head between the ears B B² and prevents the knuckles from being advanced rearwardly beyond its normal closed position by the impact of the draw-head on an adjacent approaching car, as required, to receive the force of the blow.

J is a gravity locking-latch pivoted at its upper end in the top portion of the draw-head and depending therefrom through openings formed in the draw-head.

Referring to Fig. 4, it will be observed that the latch J is curved and has a shoulder or cam J² formed thereon that will be engaged by the top surface of the knuckle-arm, as required, to pass the latch laterally to allow the point of the arm to pass the latch. The perforation J³ in the upper end thereof serves 55 as a journal-bearing to admit the pivot by which the latch is suspended. A chain K is secured to the lower end of the latch J and extends therefrom to manually-actuated operating devices (not shown) secured to the outer 60 portions of the car. A notch K² is formed in the draw-head at one side of and opening into the opening in which the latch J swings, and is adapted to admit and retain the lower portion of said latch when it is desired to keep 65 said latch out of engagement with the arm F. A slot L is formed in the free portion of the knuckle D, and vertical perforations L² therein admit a pin by which to secure a link of common form, if desired. A slot M is 70 formed in the fixed or pivoted portion of the knuckle to admit a link of common form, which is held therein by the pin D², as shown by the dotted lines in Fig. 5.

In the practical use of my invention the 75 gravity-latch J is pivoted to the draw-head in a different vertical plane from the opening in which it operates, and the tendency thereof is to swing toward the arm F. When the meeting draw-heads come in contact, the 80 knuckles will be closed within each other and automatically locked by the latch J, which resumes its normal position by force of gravity after the end of the arm F has passed in rear of it. When it is desired to uncouple 85 the cars, the latch is withdrawn from engagement with the arm F by means of the chain K, and let into the notch K² to permit the 90 separation of the cars at any time without 95 100

further attention from the train-man or yard-man. If at any time the knuckle should be closed without a coupling being effected upon the withdrawal of the latch from engagement 5 with the arm thereof, said knuckle will automatically open by reason of the meeting of the end of the journal C with the inclined bottom of the cavity in the ear B². By suspending the latch J in such a manner that it 10 will swing laterally relative to that draw-bar and providing the latch with a cam J² and the jaw with a shoulder H, and the draw-head with an opening that allows the latch to extend downward through the draw-head, and 15 a notch K², intersecting said opening, the latch can be in position, as required, to be automatically operated by the contact of the shoulder H of the jaw with the cam J² of the latch, and also retained inoperative by allowing the latch to be retained in the notch K² 20 in the draw-head. When the shoulder H at the top of the arm F of the pivoted jaw engages the cam J² of the suspended latch J, it presses upward on the cam and moves the 25 lower end of the latch laterally relative to the end of the arm F, as required, to allow the end of the arm to pass inward, and when the shoulder H is disengaged from the cam J² the latch will resume its normal position by 30 force of gravity and engage the end of the arm F, as clearly shown in Fig. 5, and as required to automatically lock the jaw.

I claim as my invention—

1. In a car-coupling, a latch having a curved 35 top end adapted to be pivoted to the draw-head and provided with a shoulder or cam at its top portion adapted to be engaged by the

top portion of the projection of a horizontally-swinging jaw, in combination with a draw-head having a cavity within which to suspend 40 the latch, and an opening in the bottom to allow the latch to project downward through the draw-head and to swing laterally relative to the draw-bar, and a pivoted jaw having an arm or projection adapted to engage and operate the latch, in the manner set forth, for 45 the purposes stated.

2. A draw-head having a transverse opening in the bottom, and an enlargement or notch K², intersecting said opening, and a 50 latch pivoted to the top portion of the draw-head and adapted to traverse said transverse opening and to rest in said notch, in the manner set forth, for the purposes stated.

3. An improved automatic car-coupling comprising a draw-head having a concave front face and a concave cavity or recess, a transverse opening in the bottom, and an enlargement or notch in the front side and outer end of the opening, a latch having a curve, and a 55 shoulder or cam at its top portion suspended in the top portion of the draw-head and extended down through the transverse opening in the bottom of the draw-head, and a pivoted jaw having an arm extending horizontally, 60 and a shoulder at its top adapted to engage the cam on the latch, arranged and combined to operate in the manner set forth, for the purposes stated.

CHARLES A. BALLREICH.
